R. H. POGUE,
STREET CAR FENDER,
APPLICATION FILED JULY 11, 1914.

1,155,682.

Patented Oct. 5, 1915.

UNITED STATES PATENT OFFICE.

ROBERT H. POGUE, OF NEW WESTMINSTER, BRITISH COLUMBIA, CANADA.

STREET-CAR FENDER.

1,155,682.

Specification of Letters Patent.

Patented Oct. 5, 1915.

Application filed July 11, 1914. Serial No. 850,479.

To all whom it may concern:

Be it known that I, ROBERT H. POGUE, a citizen of the Dominion of Canada, residing at New Westminster, in the Province of 5 British Columbia, Canada, have invented certain new and useful Improvements in Street-Car Fenders, of which the following is a specification.

This invention relates to an improved car 10 fender having provision by which the fender is automatically dropped to the track level on encountering an obstruction on the track. It belongs to that class wherein the release of the sustaining mechanism is effected automatically by an actuating bar 15 projecting in advance of the front rail of the fender.

The object of the improvement is to simplify the sustaining mechanism and to render its release operative by as light a pressure as possible on the advance bar, and to so construct it that the fender may be dropped and be restored by the motormen.

The invention is particularly described in 25 the following specification, reference being made to the drawings by which it is accompanied, in which:

Figure 1 is a side elevation of the fender in its elevated position. Fig. 2 is a front elevation of the same, the removable vertical guard being omitted. Fig. 3 is an enlarged detail of the means of suspending the fender. Fig. 4 is an enlarged detail of the means of supporting the fender in the elevated position and for effecting the release 35 and allowing it to drop to the track. Fig. 5 is a side elevation showing the fender up-folded, and Fig. 6 is a perspective view from the back of the removable vertical guard. Fig. 7 is a detail section on the line 7—7 40 of Fig. 2. Fig. 8 is a detail perspective view showing the lever abutment.

In these drawings 2 represents the front end of the car body to the under frame of 45 which the fender is connected. The fender is composed of a vertical frame having side members 3 which are connected together by an upper cross rail 4 and lower cross rail 5. To the lower end of each side member 3 50 is pivotally connected at 6, the upwardly turned end of the rail 7 which forms the front and sides of the horizontal component of the fender, the pivotal connection having a stop joint 8 that will sustain the horizontal frame in a position normal to the ver-

tical frame. The ends of the car rail 4 are partly cut away and are lapped over the side members 3 and secured to the same by screws 3* or other suitable fastenings, as best shown in Fig. 7.

The side members 3 of the vertical portion of the fender and the rail 7 of the horizontal portion may be integral, without departing from the principle of the invention, but they are preferably articulated at 6 that the horizontal portion will fold up against the vertical portion, as shown in Fig. 5, when the fender is not required, and a slip 9 is pivotally mounted on one of the stop members of the joint that may be moved 60 over the other member of the joint to fix them in the "in use" position, and a hook may also be provided to secure it in the folded or "out of use" position, as shown in Fig. 5.

The fender frame so constructed is suspended by a short link 11, see Fig. 3, from a stud pin 12 on the upper part of a stanchion 13 secured on each side of the under frame of the car and downwardly projecting therefrom, the length of the link being such as will allow the fender to fall down close to the track level and when upturned, as shown by the full lines in Fig. 3, the fender being carried a sufficient distance 80 clear of the track to avoid contact therewith under all conditions for load and oscillation.

The fender is supported in the upper position with its upper rail 4 above the pivot pin 12 on which it is suspended by the following means: Secured on each end of a rocking shaft 15 mounted in bearings in the lower part of the stanchions 13 is a lever 14, the ends of which levers are pin-connected at 16 to links 17 which are mounted free on the upper cross rail 4 of the fender frame. The end of the link 17 is produced beyond its pivotal connection and is bent around, as at 18, to engage the edge of the lever 14 and limit movement of that 90 lever forward beyond the straight line between the cross rail 4 and the rocking shaft 15. When the centers of this link connection are in the straight line the fender is supported clear of the track, but when this 100 link connection is "broken" backward the fender falls to the limit permitted by the links 11 by which it is suspended from the pins 12 of the stanchions 13 secured to the under-frame of the car body. The "break-

ing" of this lever connection may be effected from the position of the motormen within the car by a treadle lever 20 pivoted at 21 and connected intermediate of its ends by 5 a link rod 22 to a bell crank lever 23, 24 which is pivoted at 25 beneath the car underframe. The longer arm 24 of this bell crank is connected by a link rod 26 to the end of a lever 27 secured on the rocking shaft 15, so that as the treadle lever is 10 pressed down the rocking lever arm 27 is drawn back and moves with it the rocking shaft 15 and its lever 14 to "break" the supporting link connection and drop the fender.

To enable the fender to be automatically dropped to the track level by an obstruction which may be on the track, the fender is provided with an advance rail 30 which is 20 carried on two side rods 31 in advance of the front rail 7 of the fender proper, and the inner ends of these side rods 31 are pinned connected to a link 32 on each side suspended from the cross rail 4 of the fender. 25 These links 32 are in proximity to the fender supporting link connection 14, 17 so that movement of them backward, as when the advance rail 30 encounters an obstruction on the track, acts upon a projecting roller headed end 16^a of the link connecting pin 16 to "break" the connection by which the fender is supported clear of the track and allow it to fall.

The fender may be provided with a net of 35 any approved design that will resiliently receive any body which the fender may encounter; or the horizontally disposed portion of it may have thin metal slats across it, and a similar resilient frame 35 of thin 40 metal slats, see Fig. 6, may be removably secured to the vertical portion of the fender. This guard frame 35 is secured by a hook 36 which rests upon the lower cross rail 5 and the upper part has headed studs 37 which 45 pass into slots 38 in the upper end of each side member 3 of the vertical portion of the fender. Springs 39 are interposed on the studs between the edges of the slot 38 and the frame of 35. These springs are 50 designed to absorb and lessen the effect of the shock of a body striking the guard frame.

After being dropped to the track level, the fender may be readily restored to its elevated position clear of the track by the 55 motormen lifting the treadle lever 20, which movement acts on the rocking shaft 15 to restore the link connection 14, 17 to the supporting position.

The fender, owing to the method of suspending and supporting it, and of effecting its release, is particularly sensitive to the means adopted for effecting the release, and falls quickly on encountering an obstruction.

Having now particularly described my in-

vention, I hereby declare that what I claim as new and desire to be protected in by Letters Patent, is:

1. A street car fender, comprising the combination with a vertically and a horizontally disposed fender frame composed of side frames and cross rails, means for connecting the upper part of the fender to the car and for limiting its fall to the track, means for supporting the fender frame 70 clear of the track, said means comprising a rocking shaft mounted in bearings secured to the car body below the upper cross rail of the fender, a lever projecting from and in line with the end of the rocking shaft, a link 80 connecting the free end of each lever to the upper part of the fender frame, means for limiting the movement of this link connection forward beyond a straight line between the rocking shaft and the connection of the 85 links to the fender and means for "breaking" the link connection backward and allowing the fender to fall to the track.

2. A street car fender, comprising the combination with a vertically and horizontally disposed frame composed of side frames and cross rails, means for connecting the upper part of the fender to the car and for limiting its fall to the track, means for supporting the fender frame clear of the 90 track, said means comprising a rocking shaft mounted in bearings secured to the car body below the upper cross rail of the fender, a lever secured to each end of this rocking shaft, a link connecting the free end 95 of each lever to the upper cross rail of the fender, means for limiting movement of this link connection forward beyond a straight line between the rocking shaft and the connection of the link to the fender, and means 100 co-operative with a rail in advance of the front rail of the fender for "breaking" the link connection backward and allowing the 105 fender to fall to the track.

3. A street car fender, comprising the 110 combination with a vertically and horizontally disposed fender frame, means for connecting the fender to the front end of the car, said means comprising stanchions secured to the under frame of the car and projecting vertically downward from the front end thereof and carried backward and upward to the car body, links connecting the upper part of the fender frame to the upper 115 part of each stanchion, a rocking shaft mounted in bearings on the stanchions and having at each end a lever integral with or secured to it, a link connecting the free end of each rocking shaft lever with the upper 120 part of the fender frame, said link being produced beyond the pin connection to the lever and carried around the back of it to limit movement forward at the joint beyond a straight line between the rocking shaft 125 and the fender frame where the rocking 130

shaft levers are connected, an advance rail supported in front of the front rail of the fender, a rod on each end of this advance rail, a link supporting the after end of each 5 side bar from the upper part of the fender frame, the back of each link being in engagement with the adjacent joint of the rocking shaft lever end, and means operative from within the car for moving the 10 rocking shaft backward to "break" the supporting mechanism.

4. A street car fender, comprising the combination with a vertically and a horizontally disposed fender frame hinged together to enable the horizontally disposed 15 frame to fold up against the vertically disposed frame and having a stop joint at the hinge that will sustain the horizontally disposed portion at right angles to the vertically 20 disposed portion, means for suspending the vertically disposed portion from the under frame of the car in a manner that will limit its downward movement to the track level and permit it being lifted clear 25 of the track, means for supporting the fender frame clear of the track, means coöperative with a rail in advance of the front rail of the fender for releasing the support and permitting the frame to fall, and means for 30 raising and lowering the fender from within the car.

5. A street car fender, comprising the combination with a vertically and a horizontally disposed fender frame, stanchions secured to the car under frame and downwardly projecting from its front end, links connecting the upper part of the fender to the upper part of each stanchion, a rocking 35 shaft supported in bearings across the lower 40 part of the stanchions, levers secured to or integral with the rocking shaft at each end, links connecting the end of these levers with the upper part of the fender, the end of each 45 of said links where connected to the levers being produced beyond the pin connection and carried around to engage the edge of the lever to which it is connected to limit movement of the link connection beyond the straight line between the rocking shaft 50 and the link connection of it to the fender, a link suspended from the upper part of the fender adjacent to each rocking lever link, said links engaging the front of the pin connection, said bars being connected 55 to the lower ends of these links and endwise movable on the horizontal portion of the fender and a cross rail connected to the ends of the side bar and supported by them in advance of the front rail of the fender.

60 6. A street car fender, comprising stanchions secured to the car under frame and

downwardly projecting from its front end, a vertically disposed fender frame link-connected to the upper part of each stanchion against the lower part of which stanchion 65 the lower cross rail of the fender frame may bear, a horizontally disposed fender frame pin-connected to the lower part of the vertically disposed frame with a stop-joint that will sustain the horizontally disposed portion 70 at right angles to the vertically disposed frame, means pivotally connected to one frame for securing it at right angles to the other frame, a rocking shaft having a lever at each end mounted in bearings in 75 the lower part of the stanchions, a link connecting the end of each rocking shaft lever to the upper part of the vertically disposed frame of the fender, said link-connection having a stop-joint preventing movement 80 of the lever forward beyond a straight line between the rocking shaft and the link-connection to the fender frame, a cross rail supported in advance of the front rail of the fender, means for connecting this advance rail to "break" the link-connection 85 backward, and means connected to the rocking shaft for "breaking" the connection backward from within the car.

7. A street car fender, comprising the 90 combination with a vertically and horizontally disposed fender frame connected to enable the horizontal frame to fold up against the vertical frame, the connection having a stop-joint to limit movement beyond a right angle, means connecting the 95 upper part of the vertical portion of the fender frame to the car and limiting its movement toward the track, means for supporting the fender frame clear of the track, 100 said means comprising a rocking shaft mounted in bearings secured to the car body, a lever integral with or secured to each end of this rocking shaft, a link connecting the free end of each lever to the upper part of 105 the fender frame, means for limiting the movement of this link connection forward beyond a straight line between the rocking shaft and the connection of the links to the frame of the fender, means connected to a 110 rail in advance of the front rail of the fender for "breaking" the supporting link-connection backward, and means connected to a lever on the rocking shaft for "breaking" the connection from within the car. 115

In testimony whereof I affix my signature in presence of two witnesses.

ROBERT H. POGUE.
